UNITED STATES PATENT OFFICE.

HOWARD E. HARBAUGH, OF KENOSHA, WISCONSIN, ASSIGNOR TO THE CHICAGO-ROCKFORD HOSIERY COMPANY, OF SAME PLACE.

CIRCULAR-KNITTING MACHINE.

SPECIFICATION forming part of Letters Patent No. 664,266, dated December 18, 1900.

Application filed October 5, 1900. Serial No. 32,197. (No model.)

To all whom it may concern:

Be it known that I, HOWARD E. HARBAUGH, a citizen of the United States of America, residing at Kenosha, in the county of Kenosha 5 and State of Wisconsin, have invented certain new and useful Improvements in Circular-Knitting Machines, of which the following is a specification.

The object of my invention is the improvement of that class of circular-knitting machines which are well illustrated by the specification and drawings of Letters Patent of the United States No. 461,358, granted to the Sulloway Mills October 13, 1891, to which reference is hereby made as fairly disclosing the state of the art in that class of knitting-machines on or about that date.

My invention consists of certain new and useful features of construction and combinations of devices contrived and arranged to adapt knitting-machines of the class hereinbefore mentioned to knit wide and deep heels.

Referring to the accompanying drawings, which form a part of this specification, Figures 1, 1^a, and 1^b are top plan views of a machine embodying my improvements, some of the parts thereof being in different positions in each of the views. Fig. 2 is a side elevation of the machine, a portion of the latch-opening ring of the same being sectioned away, with the parts thereof in the positions shown in Fig. 1^a. Fig. 3 is a side elevation of the cam-cylinder thereof. Fig. 4 is a plan of the cam-cylinder. Fig. 5 is a rear elevation of the parts shown in Fig. 3. Fig. 6 is an elevation of the interior of the cam-cylinder, half-size, developed on a plane. Figs. 7 to 10, inclusive, are detailed top, side, and face views, respectively, of the needle elevating and depressing switch of the machine and a part of the mechanism for operating the same. Figs. 11 to 13, inclusive, are detailed views of the needle elevating and depressing switch and one of the devices for operating the same, all of which will be fully described hereinafter. Fig. 14 is a top plan view of certain needles having heels of different lengths. Fig. 15 is a detailed view of two alternately-acting cams.

Like characters of reference indicate corresponding parts throughout the several views.

A is a needle-cylinder having needle-

grooves *a* therein containing needles *a'* *a²* *a³*, provided with heels *a⁴* *a⁵* *a⁶*.

B is a cam-cylinder encircling the needle-cylinder A and provided interiorly with a circumferential ledge B^a, upon which all the needles of the machine rest while knitting round and round, and exteriorly with a bevel-gear B^b. In the interior of the cam-cylinder 55 B, above the ledge B^a, are guide-plates B² B³, above and below which the heels *a⁴* *a⁵* *a⁶* of the needles *a'* *a²* *a³* are carried as they are retired from and brought back into action, while to the outside of said cylinder B and 60 working through slots B⁴, formed in the walls thereof, are pivoted elevators and depressors B⁵ B⁶, by means whereof the needles concerned in the narrowing and widening operations are respectively carried out of or brought 65 back into action as one or the other of these operations is being effected. In their normal positions these elevators and depressors rest with their free or hooked ends B⁷ B⁸ in line with the heels of the needles in connection 70 with which they are to coöperate, and when carried out of operation by the elevation or depression of such needles they are engaged by latches C, also pivoted to the outside of the cam-cylinder B, and by them prevented 75 from returning thereinto until again released by removing the latches from engagement therewith. When the narrowing and widening operations are not being effected, the elevators and depressors are held out of action 80 or in the position shown in Fig. 6 by the aforesaid latches; but when one or the other of these operations is to be accomplished either the elevators B⁵ or the depressors B⁶, or both, as the case may be, will be released 85 from their latches C and allowed to return 90 into action ready for engagement with their appropriate needles as the cam-cylinder is reciprocated in the operation of the machine.

In all cases when the narrowing of the fabric is to be effected the elevators alone will be released from their latches and returned into operation. On the other hand, when the widening of the fabric is to be accomplished the depressors will be released from their 95 latches and similarly returned into action, the elevators in some cases being retired from operation when the depressors are brought into action and in others retained in opera-

tion therewith. When the elevators are re-tired from operation at the same time that the depressors are brought into action, the hooks B^8 of the depressors will be made of the same length as the hooks B^7 of the elevators and each will at each reciprocation of the cam-cylinder engage the heel of but a single needle; but when both the elevators and depressors are retained in action the hooks B^8 will be made of a length to engage the heels of two needles, while the hooks B^7 will be made of a length to engage the heel of but a single needle, whereby during the widening operation the depressors will at each reciprocation of the cam-cylinder bring down into operation two needles and the elevators at the next reciprocation thereof carry one of the needles thus brought down out of operation, and so on throughout the entire operation of widening.

In the drawings the hooks B^8 are shown of a length to engage the heels of two needles and the hooks B^7 of a length to engage the heel of but a single needle; but the hooks B^8 may be so proportioned as to engage the heel of but a single needle, if so desired.

In addition to the long-heeled and short-heeled needles shown and described in the specification and drawings of Letters Patent No. 461,358, referred to hereinbefore, I employ two groups of intermediate-heeled needles a^8 , located between the long-heeled and short-heeled needles. The intermediate-heeled needles a^8 coöperate with the rest of the needles of the machine to knit the legs and tubular parts of the feet of the stockings; but their particular function is to supplement the short-heeled needles a' and coöperate with them in knitting the heels of stockings in order that such stocking-heels may be formed wider and deeper than the toes thereof or of any desired width and depth within the scope of the short-heeled needles a' plus the intermediate-heeled needles a^8 . The intermediate-heeled needles a^8 are not employed in knitting the toes of stockings, the short-heeled needles a' being the only ones employed for that purpose.

To provide for releasing the elevators B^5 and depressors B^6 at the proper times to effect the narrowing and widening operations, the latches C are each equipped with a stud c , extending outward therefrom, with which suitably-arranged cam-surfaces $C^2 C^3$, under the control of a cam-controlling ring, coöperate. The cam-surfaces $C^2 C^3$ for acting upon the studs c , the pattern mechanism, and the devices made use of for operating the cam-cylinder are or may be the same as the corresponding parts shown and described in an application for Letters Patent filed by William H. Mayo and George D. Mayo October 3, 1888, Serial No. 287,063, to which reference may be had therefor.

D is a recess formed in the interior of the cam-cylinder B .

D^2 is a switch consisting of any suitable

body having formed in its inner face a longitudinal groove D^3 , which, extending throughout its entire length and tapering gradually from its outer and wider to its inner and narrower end, has its under walls D^4 cut away to such an extent as to permit of their engagement, Fig. 8, with the long-heeled and intermediate-heeled needles only, while its upper walls D^5 are extended inward toward the needle-cylinder A sufficiently to engage all the needles of the machine. The switch D^2 , Fig. 13, is mounted in proper relation to the guide-plates $B^2 B^3$ and in the recess D in the cam-cylinder B on the inner end of a rock-shaft D^5 , that is fitted both to oscillate and to slide endwise in a bearing D^6 in the supporting-bracket D^7 .

D^8 is a semipinion mounted on and secured to the free end of the rock-shaft D^5 by means of a feather D^9 and spline D^{10} .

D^{11} is a screw-stud provided with a head D^{12} , having a peripheral groove D^{13} therein and turned into the longitudinal screw-hole D^{14} in the rock-shaft D^5 .

D^{15} , Fig. 2, is a rack mounted in the vertical slideway D^{16} in the bracket D^7 , provided with an actuating-stud D^{17} and meshing with the semipinion D^8 .

D^{18} is a shifting-cam provided with oppositely-inclined faces $D^{19} D^{20}$, engaging the opposite sides of the peripheral groove D^{13} and pivotally mounted on a bearing D^{21} , Fig. 2, on the cam-cylinder B .

I do not desire or intend to limit myself to the particular form of device just described for sliding the rock-shaft D^5 endwise, as obviously other common and well-known devices could be substituted therefor without departing from the spirit and scope of my invention.

I will now describe the instrumentalities employed to operate the switch D^2 .

1 is a ring fast to the base-plate (not shown) of the machine.

2 is a cam-controlling ring resting on the upper end of the base-ring 1, whereon it may be slightly turned back and forth. The ring 2 has the cams $2^a 2^b$, stop 2^d , and lugs $2^e 2^f$ projecting from the upper face thereof.

3 and 4 are respectively downwardly and upwardly sloping cams fast to the free and adjacent ends of the two arms 5 and 6, Fig. 2, which are also provided with cam-surfaces 7 and 8 on their inner edges and mounted one above the other on the pivot 9.

10 is a lug fast to the free end of the arm 11, which is mounted by its other end on the pivot 12.

13 is a stud supporting a spring 14, which normally holds the free end of the arm 11 into contact with said stud 13.

15 is a vertical rock-shaft provided with an arm 16, projecting horizontally therefrom against the arm 11. The rock-shaft 15 is turned at predetermined intervals by appropriate pattern mechanism (not shown) sufficiently to cause the free end of the arm 16 to

press the free end of the arm 11 inward against the action of the spring 14 until the lug 10 is projected into the path of the lower end Y of the shifting-cam D¹⁸. After the latter, acting through the rock-shaft D⁵, has moved the switch D² endwise from the position shown in Fig. 8 to that shown in Fig. 7 the arm 16 is turned by said pattern mechanism out of engagement with the arm 11, 10 which is then swung in the opposite direction, by the action of the spring 14, over against the stud 13, where it will remain until again pressed inward, as before, by the arm 16.

18 is a stop-lever mounted near its central portion on a stationary horizontal pivot 19, supported by the vertical lug 19^a on the machine-frame. (Not shown.)

20 is a spring normally elevating the inner end of the stop-lever 18 into the path of the 20 stop 2^d.

21 is a vertically-moving releasing-pin located below the outer end of the stop-lever 18. The lower end of the releasing-pin 21 is in contact with appropriate pattern mechanism which forces it at predetermined intervals upward against the outer end of the stop-lever 18, thereby tilting the inner end of the latter downward against the action of the spring 20 out of engagement with the lug 2^d. 25 The pattern mechanism also at predetermined intervals so acts as to permit the pin 21 to descend, and the spring 20 again forces the inner end of the lever 18 upward into the path of the lug 2^d.

35 22 is a cam mounted on a vertical pivot 22^a on the base-ring 1. The function of the cam 22 is to turn the cam-controlling ring 2 a short distance against the action of the spring 23, which normally acts to turn said ring 2 a short 40 distance in the opposite direction.

45 24 is an arm pivotally connecting the outer end of the cam 22 at 25 with appropriate pattern mechanism, which at predetermined intervals forces the cam 22 against the lug 2^d on the ring 2 and turns it a short distance against the action of the spring 23. Also at predetermined intervals the pattern mechanism permits the spring 23, by disengaging therefrom the cam 22, to return the ring 2 to 50 its normal position.

When it is desired to retire the long-heeled needles a² from operation preparatory to knitting the heel of a stocking, the switch D², being in the longitudinal position shown in 55 Figs. 7 and 9, will be turned downward until the outer and wider end of the groove D³ therein is brought into line with the heels a⁶ as they rest upon the ledge B^a, in which position its under walls D⁴ as the cam-cylinder is rotated engage such heels a⁶ only and deflect them upward above the guide-plates B² B³, thereby carrying them, with their respective needles, out of action. The long-heeled needles a² having been thus returned, 60 the intermediate-heeled and short-heeled needles a³ a⁴ are left to knit a heel wider by ten stitches and deeper by ten rows of stitches

than the toe of the stocking, the knitting of which will be described hereinafter. After the heel has been knit by the intermediate-heeled and short-heeled needles a³ a⁴ the switch D² will be turned upward and slid inward endwise to the position shown in Fig. 8 and indicated by dotted lines in Fig. 10. Thereafter its upper walls D⁵ as the cam-cylinder is rotated engage the heels a⁶ of the long-heeled needles a² and deflect them downward onto the ledge B^a, thereby leaving all the needles of the machine in proper position to knit the tubular portion of the foot 80 of the stocking. When the tubular portion of the same is completed, the switch D², still being in the position shown in Fig. 8, will be turned downward to the position shown by solid line in Fig. 10 until the outer and wider 85 end of the groove D³ is brought into line with the heels a⁵ a⁶ of the intermediate-heeled and long-heeled needles a³ a² as they rest upon the ledge B^a, in which position its upper walls D⁵ as the cam-cylinder is rotated engage such 90 heels a⁵ a⁶ only and deflect them upward above the guide-plates B² B³, thereby carrying them, with their needles a³ a², out of action. The short-heeled needles a⁴ alone are thus left in action, and the machine proceeds 95 to knit the toe of a stocking, which will be narrower by ten inches and shallower by ten rows of stitches than the heel to the knitting of which reference is made above.

The general construction and mode of operation of the machine to which I have applied my improvements are the same as those shown and described in Letters Patent of the United States No. 461,358, granted to the Sulloway Mills October 13, 1891, to which reference has already been made in the second paragraph of this application and to which reference may be had therefor.

Fig. 1 shows the parts of the machine in position to knit the leg of a stocking, the cam-surfaces C² C³ being beyond the reach of the studs c, the switch D² being in the position shown in Fig. 8 and indicated by dotted lines in Fig. 10 and the shifting-cam D¹⁸ in the position shown in Fig. 2. Supposing the leg 115 to be finished and that the machine is about to begin the knitting of a heel, the pattern mechanism, acting through the arm 24, disengages the cam 22 from the lug 2^e and the spring 23 turns the cam-controlling ring 2 in 120 the direction of the arrow, Fig. 1^a, until the stop 2^d thereon strikes the stop-lever 18. As the ring 2 is turned by the spring 23 the edge conformation of the cam 2^a permits the cam-surface C³ to move inward into the path of 125 the two studs c, which, acting through their latches C, release the needle-elevators B⁵, the spring 25 presses the downwardly-sloping cam 3 inward into the path of the actuating-stud D¹⁷ on the rack D¹⁵, and the lug 2^f, acting on the cam 8 on the arm 6, forces the cam 4 outward against the action of the spring 26. Simultaneously with changes just described 130 the pattern mechanism turns the rock-shaft

15 in the direction indicated by the arrow, Fig. 1°, and forces the free end of the arm 16 against the arm 11, thereby throwing the lug 10 into the path of the lower end Y of the shifting-cam D¹⁸. As the cam-ring B makes its last rotation, traveling in the direction contrary to that traveled by the hands of a watch, to knit the leg of the stocking, the lug D¹⁷ strikes the downwardly-inclined cam 3, which forces such lug and its rack D¹⁵ upward from the position shown in Fig. 2 to the position shown in Fig. 9. The upward movement of the rack D¹⁵, acting through the semi-pinion D⁸, turns the switch D² from the position shown in Fig. 8 and indicated by dotted lines in Fig. 10 to the position shown by solid lines in Fig. 10. Immediately after the switch D² has been turned down in the manner already indicated the lower end Y of the shifting-cam D¹⁸ strikes the lug 10, which rocks such cam D¹⁸ from the position shown in Fig. 8 to that shown in Fig. 7, which rocking motion disengages the inclined cam-face D¹⁹ from and forces the inclined cam-face D²⁰ into engagement with the opposite walls D²² D²³, respectively, of the groove D¹³ in the screw-head D¹², thereby sliding the switch endwise from the position shown in Fig. 8 to that shown in Figs. 7 and 9. Figs. 7 and 9 show the switch D² in proper position, with the broad end of the groove D³ turned down to the ledge B⁴, Fig. 10, for the cam-cylinder B² to continue its operations. Fig. 8 shows the switch D² turned upward, as indicated by dotted lines in Fig. 10. Suppose now the switch D² to be in all respects in the positions shown in Figs. 7 and 9 and that the cam-ring B has begun to oscillate. At the end of the first complete oscillation of such cam-ring B, the long-heeled needles a² will have been deflected, by the switch D², above the guide-plates B² B³, and out of action; but the intermediate-heeled needles a³ and all but about the middle thirty of the short-heeled needles a' have gone up, out of action, to join the long-heeled needles a², through the operation of the needle-elevators B⁵, the releasing-pin 21 of the stop-lever 18, and the inner end of the same is thus depressed a corresponding distance, below the stop 2^d against the action of the spring 20. The cam-controlling ring 2, being thus left free to turn, is turned by the action of the spring 23 until it is stopped by the cam 22 coming in contact with the stop 2^d. The movement of the cam-controlling ring 2 just described permits the the cam-surface C² to swing inward into the path of the two studs c, which, acting through their latches C, release the needle-depressors B⁶, which depress into action the short-heeled and intermediate-heeled needles a' a³, that went out of action when the first half of the heel was being knit. The return of the last-mentioned needles having been completed, the heel will have been completed also. The pattern mechanism, acting through the arm 24 and cam 22, then forces the cam-control-

ling ring 2, against the action of the spring 23, into the position shown in Fig. 1, and all parts of the machine are thereby restored to the positions there shown. As the cam-controlling ring 2 turned to the last-mentioned position, the lug 2^f, engaging the cam 7 on the arm 5, forced the downwardly-inclined cam 3 back against the action of the spring 25 and 75 out of the path of the lug D¹⁷ on the rack D¹⁵ and passed down the cam 8 on the arm 6, the spring 26 forcing the upwardly-inclined cam 4 inward into the path of the lug D¹⁷ on the rack D¹⁵. As the last course of stitches on 80 the heel was being knit, the upwardly-inclined cam 4 passed over the lug D¹⁷ on the rack D¹⁵ and forced it down to the position shown in Fig. 2. The descent of the lug D¹⁷ and rack D¹⁵ also rocked the shifting-cam D¹⁸ to the 85 position shown in Fig. 2, thereby turning the switch D² and sliding it inward endwise to the positions shown in Fig. 8 and indicated by dotted lines in Fig. 10. When the cam-ring B began to rotate, the switch D² deflected the long-heeled needles a² down onto the ledge B⁴, where the intermediate-heeled and short-heeled needles a³ a' had already gone through the operation of the needle-depressors B⁶. The cam-ring B continues to rotate 90 until the round part of the foot of the stocking is completed. The machine then knits the toe of the stocking in precisely the same manner that it knitted the heel thereof, except that only the short-heeled needles a' remain in action and are employed to knit the toe. The arms 11 and 16 remain in the positions shown in Fig. 1 during the knitting of the toe, the rock-shaft 15, in fact, being operative only just before the machine begins to 105 knit the heel, and since the switch D² will remain in the endwise position shown in Fig. 8 until the lug 10 on the arm 11, acting through the shifting-cam D¹⁸, slides the switch D² endwise outward again, and since the lug D¹⁷ on the rack D¹⁵ will pass over the downwardly-inclined cam 3, which turns the switch D² from the position shown in Fig. 8 to the position shown in solid lines in Fig. 10, just before the machine begins to knit the toe of 115 the stocking, obviously, the switch D² being in the positions just indicated, the long-heeled and intermediate-heeled needles a² a³ will be deflected by the groove D³ therein up above the guide-plates B² B³ and out of action, thus leaving only the short-heeled needles a' in action to knit the toe of the stocking. 120

Having described my invention and indicated of what it consists, what I claim as new, and desire to secure by Letters Patent of the 125 United States of America, is—

1. In a knitting-machine, in combination, a cam-cylinder, a needle elevating and depressing switch mounted, on the interior thereof, on a rock-shaft adapted to be reciprocated endwise, and means for reciprocating such rock-shaft and switch endwise, substantially as and for the purpose specified. 130
2. In a knitting-machine, in combination,

5 a cam-cylinder, a rock-shaft adapted to be slid back and forth endwise in a bearing in the interior thereof, a needle elevating and depressing switch mounted on the inner end of said rock-shaft and a switch-cam for sliding said rock-shaft and switch back and forth, substantially as and for the purpose specified.

10 3. In a knitting-machine, in combination, a cam-cylinder, provided with a circumferential ledge and with guide-plates located above the same, needles having heels of three different lengths, and a switch consisting of a body provided in its face with a tapering groove, the under walls whereof are cut away 15 to reduce their height, said cam having an endwise movement outward, whereby it is made to deflect the long-heeled needles upward upon the guide-plates, leaving the intermediate-heeled and short-heeled needles 20 to knit a wide and deep stocking-heel, substantially as and for the purpose specified.

25 4. In a knitting-machine, in combination, a cam-cylinder, needles having heels of three different lengths—the intermediate-heeled needles being located in two groups, between the group of long-heeled and the group of

short-heeled needles—and a switch consisting of a body provided in its face with a tapering groove, the inner walls whereof are cut away to reduce their height, said cam having an 30 endwise movement outward, whereby it is caused to deflect the long-heeled needles upward out of action, leaving the intermediate-heeled and short-heeled needles in action to the heel of a stocking, substantially as and 35 for the purpose specified.

5. In a knitting-machine, in combination, a cam-cylinder, a rock-shaft adapted to be slid back and forth endwise in a bearing in the interior thereof, a needle elevating and 40 depressing switch mounted on the inner end of said rock-shaft, and a switch-cam for sliding said rock-shaft and switch back and forth, and means for operating said switch-cam, substantially as and for the purpose specified. 45

In testimony whereof I have signed my name to this specification in the presence of two subscribing witnesses.

HOWARD E. HARBAUGH.
